UNITED STATES PATENT OFFICE

2,433,322

GAG PRESS

Edward T. Peterson, Reading, Pa., assignor to
Birdsboro Steel Foundry & Machine Co., Birds-
boro, Pa., a corporation of Pennsylvania

Application May 4, 1944, Serial No. 534,175

5 Claims. (Cl. 153—48)

1

The invention pertains to a gag press incident to the fabrication of steel and particularly the straightening operation of billets and the like.

An object of the invention is the provision, in a gag press, of a billet manipulator whereby a billet out of true alignment can be rotated about its normal longitudinal axis so as to subject it to the action of a ram in the course of the straightening process thereof.

Another object of the invention is to provide, in a gag press, a billet manipulator arranged to support a billet for substantially its entire length and rotate the billet so that it may be acted upon by a straightening ram.

A further object of the invention is to provide, in a gag press, a billet manipulator located in the path of a billet and between an approach table and a run out table so that the billet may be picked up in its travel and rotated as desired.

Still another object of the invention is the provision, in a gag press, of a billet manipulator having portions thereof disposed below conveyor means and arranged so that a billet may be picked up from the conveyor, rotated a certain desired degree and deposited on the conveyor.

These and other objects of the invention will become apparent from the succeeding description considered together with the accompanying drawings wherein:

Figure 1 is a partial plan view of a gag press embodying the present invention.

Figure 1A is a continuation of the gag press shown in Figure 1 and showing that portion of the gag press to the right of Figure 1.

Figure 1B is a continuation to the left of the gag press shown in Figure 1.

Figure 2 is a vertical sectional view taken along the lines 2—2 of Figure 1, looking in the direction of the arrows.

Figure 2A is a vertical sectional view taken along the lines 2A—2A of Figure 1, looking in the direction of the arrows.

Figure 2B is a vertical sectional view taken along the lines 2B—2B of Figure 1A, looking in the direction of the arrows.

Figure 3 is a transverse sectional view taken along the lines 3—3 of Figure 1A, looking in the direction of the arrows.

Figure 4 is a transverse sectional view taken along the lines 4—4 of Figure 1, looking in the direction of the arrows.

Figure 5 is a transverse sectional view similar to the disclosure in Figure 4 except that the related parts are in another than normal relationship.

2

Figure 6 is a partial transverse sectional view taken along the lines 6—6 of Figure 2A, looking in the direction of the arrows.

By referring now in detail to the accompanying drawings which disclose an exemplified form of the invention, and wherein like reference characters indicate like parts, the numeral 1 is employed to designate in a general manner, a gag press, forming a component in the manufacture of steel and more particularly adapted to straighten billets and the like. By considering generally the gag press so as to afford a clear understanding of the invention, billets 2, indicated diagrammatically, are deposited by a crane (not shown) or any other means on a loading platform or bed 3 which comprises conveniently spaced supports 4 each having associated ends of horizontally disposed transverse skids 5 arranged in pairs and secured to the supports. The opposite ends of the skids are firmly fastened to and supported by an underlying foundation beam 6 extending horizontally and longitudinally of the gag press. Interposed between each pair of skids is a shuffle bar 7 having one end thereof riding upon or between suitable wheels 8 which are carried by the supports so as to render the shuffle bar freely movable. The opposite end of the shuffle bars are fastened securely to a longitudinally disposed underlying cross bar 9 which joins all of the shuffle bars and is connected to an eccentric shaft 10 arranged, upon rotation, to impart an oscillatory and rotary motion to the shuffle bars. In this manner, therefore, billets are progressively raised from the skids and moved toward the extremity of the skids removed from the supports.

Acting as a billet receiving medium or an approach table are a plurality of delivery conveyor forming rollers 12 extending transversely of the gag press and conveniently spaced longitudinally thereof in the proximity of the free or delivery end of the loading bed, so that successive actions of the shuffle bars will result in the deposit of a billet or billets on the rollers or delivery conveyor. The rollers 12 have their related extremities suitably accommodated by table girders supported bearings 13 while the other extremities are similarly carried so as to render the rollers easily rotatable. The last named extremities of the delivery conveyor rollers are associated with housings 14 encasing suitable beveled gears (not shown). A line shaft 15 extends through all of the housings and is joined to the beveled gears so as to be arranged to impart motion thereto. A driving mechanism 16, comprising a motor 16a and reduction gears (not shown) within a hous-

ing 16b is operatively connected to the line shaft 15 so that a movement of the motor will be reflected in a rotary action of the delivery conveyor rollers. Adjacent to an inner extremity of the delivery conveyor is a buffer bar or swinging guide 17 so that upon movement of a billet along the delivery conveyor it will be steered or directed into a restricted predetermined path in its travel along the gag press. A roller 12a of shorter extent than the rollers 12 is also operatively connected to the line shaft but is positioned beyond the swinging guide to form a portion of the delivery conveyor and function as a billet support beyond the buffer bar.

Disposed adjacent to the short roller 12a of the approach table is a press proper 18 comprising a framework 19 having as a part thereof two dies 20 suitably spaced longitudinally of the gag press. Arranged through suitable mechanism to move transversely in a path between the dies is a plunger or ram 21 so that as billet is manipulated along its path of travel and a straightening operation becomes necessary, the ram is actuated toward the dies to act upon the portion of the billet spanning or bridging the dies. Two idling rollers 22 are associated with the press 18 so as to be in supporting relation with that portion of the billet immediately over the press in the area of the dies and ram. After the billet is completely straightened it is moved longitudinally of the press on to a run out table 23 which, in effect, forms a longitudinal extension or continuation of the approach or delivery table. The run out table is desirably formed by a series of receiving conveyor rollers 24 intermittently spaced longitudinally of the gag press and having associated extremities suitably journaled in bearings 25 mounted upon a table girder 26. The other extremities of the rollers are suitably journaled and associated with gear boxes 27 which house intermeshing beveled gears (not shown). Extending through the gear boxes 27 is a line shaft 28 operatively connected to all of the related gears so that all of the receiving conveyor rollers can be rotated in unison. A driving arrangement comprising a motor 29 and gear means 30 is operatively connected to the line shaft 28 so that an action of the motor will result in a rotary motion of the rollers 24. An abutment, bulkhead or stop 31 is disposed in the line of travel of a straightened billet in the proximity of the run out table so as to form a barrier against a continued movement of a billet beyond a certain predetermined position. A knick-off head 32 is disposed longitudinally of the gag press and positioned adjacent the run out table. This kick-off head is connected, through the media of shafts and suitable levers 33, with a motor 34 so that upon actuation of the motor 34 the knick-off head will be urged transversely of the gag press across the run out table to push a finished or straightened billet or billets off of the run out table to receiving billet cradles 35 from whence they are removed by a crane (not shown) or any other suitable means for the purpose of storing or further processing or fabricating as may be desired.

It is to be noted that when a billet requires straightening and is placed upon the loading bed, the billet may be, and most generally is, distorted in more than one direction from its normal longitudinal axis. In such cases, therefore, it becomes necessary to provide or incorporate means in the arrangement whereby a billet, during the time of operation after being subjected to the action of the ram in the actual straightening operation, may

be so manipulated or physically moved to a position as to make the subsequent action of the ram effective for the purpose intended. The manipulator means must also be of such design and arrangement that a billet of round or square cross sectional configuration may be effectively rotated.

With the above, therefore, in mind, there has been incorporated in the tables adjacent to the press, a billet manipulating mechanism or means generally designated as at 36 and comprising a pair of stands 37 suitably spaced apart and disposed on each side of the press 18. The stands, desirably of cast form, are anchored securely to the foundation and are arranged in a row or alignment longitudinally of the gag press at a side thereof removed from the ram. Each stand is provided with spaced upstanding arms 38 forming bearing brackets for the accommodation of a horizontal pin 39 spanning and removably held within the arms by any desired means or method. Pivotally secured to each stand through its related pin is an associated bushing lined hub 40 of a cradle 41 which is directed substantially horizontally and transversely of the gag press. It will be noted that the stands are so arranged and disposed that each cradle is extended into the area between two related conveyor forming rollers and that the pair of cradles to the right of the press proper, when viewing the Figure 1 series of the drawings, are interposed between rollers of the approach table while the pair of cradles to the left of the press proper are interposed between various rollers of the run out table. By this arrangement, an appreciable distance in and about the area of the press is spanned by the cradles to adequately, properly and effectively underlie the area occupied by an overlying billet.

Each cradle has an upper portion 42 thereof formed by side walls 43 joined at an inner extremity by the hub 40 while what might be termed as the outer extremity of each cradle is formed by a connecting end wall 44. A top wall 45 extends from each hub for an appreciable distance toward the related end wall, where it terminates in a re-entrant flange 46 spaced from and substantially parallel with the end wall to thereby present a rigid component of the manipulator means. Angularly disposed ribs 47 also join related side walls to rigidify the cradles against stresses to which they will be subjected in service.

Bridging the side walls intermediate the end walls and reentrant flange of each cradle is a pair of parallel spaced shafts 48 having extremities cupped in suitable semi-circular bearings formed in the upper limits of the side walls. Top half bearing forming caps 49 adequately and removably secured in place through the medium of any desired means overlie the shaft extremities to complete full bearings and permit a free running of the shafts. Suitably secured through the key 50 to each shaft is a rotating means, roll or roller 51 so that each cradle has adjacent one extremity in the proximity of the conveyors a pair of spaced rotating means, rolls or rollers arranged or disposed transversely of the gag press and responsive to any motion of the related shafts. Each rotating means, roll or roller is preferably made in the form of a pulley or grooved roller and in this regard each roll or roller is provided with a circumambient recess or groove 52 which may, if desired, be provided with serrations or teeth (not shown). Extending around, connecting or joining each set or pair of rolls is a chain 53 located within the roll groove and interlocked

with the teeth or serrations if they are provided and which may be of an ordinary type of chain. A certain degree of slack is provided in the chain for the purpose to be hereinafter explained and because of this sag or slack a support plate 54 is disposed in underlying relation with the bottom flight or portion of the chain to maintain that portion in an elevated position out of the way of related structure. Securing means 55 is employed to hang the support plate from an associated cradle side wall. It is to be noted that the top flight of the rolls or rollers of each set which is represented by the diagrammatic line B as well as the flight of each chain, represented by the diagrammatic line C, is normally below the top flight of the rollers of the approach and run out tables represented by the diagrammatic line marked A so that the billets may be moved along the tables free from any interference by the manipulator.

Means has been incorporated in the manipulator to drive the roll or rollers and chain combinations and toward the accomplishment of this end each shaft is preferably provided with a fixed pinion 56 disposed between a roller and a related side wall of the cradle. Suitably journaled to the side walls of each cradle below the plane of the rolls or rollers is an intermediate gear 57 which intermeshes with the related pinions 56. Each intermediate gear which is rotatably associated with a locked, side wall supported and bridging axle 58 has a hub 59 extending therefrom to the proximity of an associated side wall so as to prevent an unwarranted shifting of the intermediate gear from its predetermined pinion meshing position. Each gear, therefore, is maintained in a fixed position between the adjacent side walls. So as to facilitate assembly of the cradles, each cradle is desirably provided with a lower or bottom portion 60 removably secured to the upper portion by means of bolts 61 and with the line of juncture between the top and bottom portions offset as at 62 to insure a proper and predesignated assembly of the two portions. A lower portion generally comprises a bottom wall 63 having rising therefrom sub-side walls 64 which are joined by diverging end webs 65 to form a rigid box-like structure capable of withstanding the stresses to which it will be subjected in service. The side walls of the top portion and the sub-side walls of the lower portion are provided with facing semi-circular bearing forming hubs 66 shown in Figures 2 and 2A with the line of demarcation therebetween being common to the line of juncture 62 so that when the two portions are in assembled relation a full bearing will be formed while upon disassembly complete half bearings will be present in each portion.

Extending through all of the cradles and properly journaled in or supported by the bearing forming hubs, is a drive shaft 67 having removably secured thereto through the medium of keys 68, bottom or drive gears 69. Each drive gear is in meshed relationship with an adjacent intermediate gear 57 so that any rotary motion imparted to the drive shaft will be reflected in the chain and rolls or rollers. This arrangement also provides for all of the chains and rolls to be driven in unison. So as to prevent a shifting of the drive shaft longitudinally of its axis, a preferably single collar 70 (see Figure 2A) is removably secured to the drive shaft and occupies the area between one of the drive gears and its opposed bearing forming hub. The drive shaft 75

extremity, in the proximity of the approach table or delivery conveyor, is provided with a coupling 71 which is connected to an inclined spindle 72 provided at its other end with another coupling 73; both couplings 71 and 73 are of a flexible type to form universal joints. This last named coupling is operatively connected to a gear type motor 74 of any desired characteristics so that any action on the part of the motor will, through the connected components, be reflected in a rotary motion in the roll or rollers and a travel of the chains.

As previously indicated, the flight of the rolls as well as the flight of the chains are normally below the flight of the approach and run out tables and in order to effect a turning or manipulating action of a billet, means is incorporated in the gag press to elevate the flight of the rolls and chain above the flight of the tables. Toward the accomplishment of this end, therefore, each lower cradle portion is provided with spaced, jaw-forming lugs 75 (see Figures 2, 2A, 4 and 5) depending from a related bottom wall and suitably apertured to accommodate a wrist pin 76. Pivottally associated with each wrist pin is a substantially vertical link or arm 77 so that each cradle is provided with an individual link. Spaced below each cradle is a stand or bearing support 78 which functions as an anchor for a related portion of an uninterrupted eccentric means or crank shaft 79 having portions thereof forming journals for the lower extremities of the links or arms. The crank shaft is connected to and driven by a suitable motor means 80.

From the foregoing it will be noted that as a billet is moved to a desired position within the range of the press ram and a turning action of the billet is required to position properly the billet for an effectual straightening operation, the motor 80 will be started to thereby raise the manipulator whereby the billet resting upon the conveyors will be picked up by the rolls and chain combinations, raising the billet from the conveyors. A manipulation of the gear motor 74 will cause the rolls and chain combinations to move, and in this manner the billet will be rotated about its normal longitudinal axis. That is to say, in actual practice it has been found that when the chain and roller combinations are manipulated the billet, by reason of it resting upon the sagging part of the chain, will have one face thereof urged upwardly along the raised or higher portion of each of one roller in a combination, thereby tilting the billet to such an extent that the billet will eventually be rotated about its axis. The rolls and chain combinations lend themselves toward the rotating of either a round or square billet, since the round billet will bear against the outer or peripheral surface of the rolls, while a square billet will have a corner thereof engaged by the chains to effect a rotation of the billet. After the elevated billet has assumed the desired position a continued action on the part of the motor 80 will result in the billet and its supporting structure being lowered where it will once more rest upon the conveyors and be subjected to the action of the ram.

From the foregoing it will be clearly understood that various changes and alterations may be made to the illustrated and described construction without departing from within the spirit of the invention and scope of the appended claims.

I claim:

1. In a billet manipulator, the combination of,

a series of supports, a series of aligned cradles each having an end thereof pivotally secured to one of said supports, conveyor means arranged to move a billet over said cradles and having a flight in a plane spaced above related extremities of said cradles, each cradle having a related extremity associated with said conveyor, a plurality of roller means journaled in each cradle, chain means joining related roller means and being disposed below the periphery of said roller means, actuating means carried by each cradle joined to said roller means, drive means extending through and carried by all of said cradles for imparting motion to said actuating means, and means for moving said cradles so that portions of said endless means will be positioned above the flight of said conveyor means.

2. In a gag press having spaced dies and a ram head disposed oppositely from said dies and arranged to move in a path between said dies, the combination of, a conveyor for carrying billets within the range of said dies and ram head, a plurality of stands, cradles spaced on each side of said ram head and each having one end thereof pivotally secured to a stand, roller means carried by each of said cradles adjacent said conveyor, said roller means being spaced transversely of said conveyor, endless chain means connecting related roller means and being disposed below the periphery of said roller means, means for driving all of said roller means, and elevating means connected to said cradles for raising a flight of said roller means and endless chain means above a flight of said conveyor.

3. In a gag press having spaced dies and a ram head disposed oppositely from said dies, the combination of, spaced rotatable conveyor means disposed longitudinally of said gag press on each side of said dies and ram head, a series of cradles interposed between certain rotatable conveyor means and positioned on each side of said dies and ram head, pivot means anchoring one end of each cradle, transversely spaced grooved roller means carried by each cradle removed from said pivot means, slack link means circumambient associated roller means and disposed below an outer surface of said roller means within grooves thereof, gear means within each cradle

and associated in driving relation with associated roller means, driving means extending through and carried by all of said cradles for rotating said gear means, and eccentric means pivotally connected to said cradles for raising a top flight of said slack link means above a top flight of said rotatable conveyor means.

4. In a billet manipulator, the combination of, a cradle journaled at one extremity, conveyor means spaced from said cradle journal, means comprising spaced rollers journaled in said cradle, slack chain means within and connecting said rollers, said slack chain means being arranged to support a billet and move the latter along the periphery of one of said rollers for the manipulation thereof, means carried by said cradle for driving said rollers, and means connected to said cradle for raising said rollers above said conveyor means.

10 5. In a billet manipulator, the combination of, a cradle journaled at one extremity, conveyor means disposed adjacent the other extremity of said cradle, transversely spaced rotatable means journaled in said cradle in the proximity of said conveyor means, endless chain means joining said spaced rotatable means and being disposed below the periphery of said rotatable means, said chain means being arranged to move a billet along the periphery of one of said rotatable means for turning the billet about its axis, drive means carried by said cradle for moving said rotatable means and endless chain, and lifting means connected to said cradle for elevating a billet above said conveyor means.

20 6. In a billet manipulator, the combination of, a cradle journaled at one extremity, conveyor means disposed adjacent the other extremity of said cradle, transversely spaced rotatable means journaled in said cradle in the proximity of said conveyor means, endless chain means joining said spaced rotatable means and being disposed below the periphery of said rotatable means, said chain means being arranged to move a billet along the periphery of one of said rotatable means for turning the billet about its axis, drive means carried by said cradle for moving said rotatable means and endless chain, and lifting means connected to said cradle for elevating a billet above said conveyor means.

35

7. In a billet manipulator, the combination of, a cradle journaled at one extremity, conveyor means disposed adjacent the other extremity of said cradle, transversely spaced rotatable means journaled in said cradle in the proximity of said conveyor means, endless chain means joining said spaced rotatable means and being disposed below the periphery of said rotatable means, said chain means being arranged to move a billet along the periphery of one of said rotatable means for turning the billet about its axis, drive means carried by said cradle for moving said rotatable means and endless chain, and lifting means connected to said cradle for elevating a billet above said conveyor means.

25 8. In a billet manipulator, the combination of, a cradle journaled at one extremity, conveyor means disposed adjacent the other extremity of said cradle, transversely spaced rotatable means journaled in said cradle in the proximity of said conveyor means, endless chain means joining said spaced rotatable means and being disposed below the periphery of said rotatable means, said chain means being arranged to move a billet along the periphery of one of said rotatable means for turning the billet about its axis, drive means carried by said cradle for moving said rotatable means and endless chain, and lifting means connected to said cradle for elevating a billet above said conveyor means.

30 9. In a billet manipulator, the combination of, a cradle journaled at one extremity, conveyor means disposed adjacent the other extremity of said cradle, transversely spaced rotatable means journaled in said cradle in the proximity of said conveyor means, endless chain means joining said spaced rotatable means and being disposed below the periphery of said rotatable means, said chain means being arranged to move a billet along the periphery of one of said rotatable means for turning the billet about its axis, drive means carried by said cradle for moving said rotatable means and endless chain, and lifting means connected to said cradle for elevating a billet above said conveyor means.
